UNITED STATES PATENT OFFICE

CLYDE B. TRUSSELL, OF OMAHA, NEBRASKA

PRINT WASHER

Application filed September 17, 1928. Serial No. 306,561.

This invention relates to a print washer for the use of photographers, and has for its object to provide an apparatus which will be convenient in use and will be effective in operation for washing and removing all acids from the prints.

One of the objects is to provide a rotatable washer which may be attached to a service pipe of a water works system, these service pipes being generally found in offices, workshops and photograph galleries.

Another object is to provide such a construction that the prints, while confined in the washer, may move freely therein and will be presented at various angles to the flow of water which moves against them to effect a thorough washing and cleansing.

Still another object is to provide an apparatus for washing photographic prints which will dispense with manual handling of the prints.

The invention includes an apparatus for washing prints which consists of few and simple parts so that it may be manufactured at a limited expense and will be durable in use.

With the above objects in view and others to be mentioned hereinafter the invention presents a new and useful construction, combination and arrangement of parts as described herein and claimed and as illustrated in the accompanying drawing, it being understood that changes may be made in size, proportion and minor details, said changes being determined by the scope of the invention as claimed.

In the drawing, Fig. 1 is a view of the print washer in longitudinal section. Fig. 2 is a view of the same in transverse section. Fig. 3 is a plan view of the print washer.

Referring now to the drawing for a more particular description, I provide a receptacle 4 for containing water and through which water may be moved, its bottom 5 having a longitudinal curvature as best shown in Fig. 1 of the drawing to facilitate the movement of flowing water. This receptacle may be constructed to advantage of sheet metal. It preferably is provided at its top with a rolled edge as indicated at 6, and may be supported

in an upright position by any suitable means, a base 7 of any suitable material being provided for this purpose.

Numerals 8 indicate an intake water pipe which projects downwardly from the top of the receptacle to terminate near its curved bottom, its upper end being arranged for removable connection with a service-pipe 9 provided with a valve 10. Numeral 11 indicates an overflow spout for the receptacle.

Numeral 12 indicates a curved deflecting-plate which projects downwardly from the top of the receptacle and terminating adjacent to the lower end of the supply-pipe 8, said plate being secured at its ends to the opposed sides of the receptacle.

I provide a holder or cage now to be described for containing the photographers prints, said holder consisting, in part, of an axle 13 provided with an enlarged part or cylinder 14, said axle being journalled in a pair of bearings-blocks 15 which are secured to the sides of the receptacle.

Numerals 16 indicate numerous U-shaped holder-bars disposed radially of and having their ends mounted in the cylindrical body. At 17 are indicated a group of U-shaped holder-bars pivotally mounted at their ends in the cylindrical body 14, and at 18 are indicated a second group of U-shaped holder-bars which are also pivotally mounted at their ends in said body 14.

I provide a pair of flexible strands or chains 19 for connecting the U-shaped bars 16 with each other. Also I provide a pair of flexible strands or chains 20 for connecting the U-shaped holder-bars 17 with each other and with a bar 16, and at 21 are indicated a pair of chains which connect the U-shaped bars 18 with each other and with one of the bars 16.

The U-shaped bars may be constructed of wire to advantage. According to the construction described the bars 16 will be disposed radially and uniformly, spaced apart, and on account of their mounting they will remain rigid with the cylindrical body 14 and axle, and if the axle is rotated the bars 16 will be moved thereby.

It will be seen that the U-shaped bars 17

are connected to form a group or section, and may be swung on their pivotal mounting. Also the U-shaped bars 18 which are connected one with the other may have swinging movements.

5 Numerals 22 indicate a pair of springs which operate to cause the groups of bars 17 and 18 to move toward each other, and in operation when it is desired to place the 10 photographic prints in the cage or holder mentioned, the springs, are detached from the bar of one of the sections 17 or 18. The bars of these sections 17 and 18 are then 15 swung downwardly to provide an adequate opening between said sections. The prints are then placed in the cage through said opening.

10 The holder-bars 17 and 18 of said sections are then swung upwardly and the springs 20 22 are then placed in position to connect the parts as shown in Figs. 1 and 3 of the drawing, water is then permitted to flow 25 into the receptacle through the curved supply-pipe 8, the result being that the cage will rotate in the direction indicated by the arrow shown in Fig. 1. The receptacle will be filled with water which will be discharged 30 from the spout 11. The prints will be moved in the cage without injury and without any 35 attention of an operator, the acid being removed from the prints, and fresh water being supplied for thoroughly cleansing the prints.

40 The U-shaped holder-bars may be connected at their sides by flexible strands 23 to confine the prints within the cage. However this is not an important feature. Numerals 45 24 indicate flexible strands for connecting the U-shaped bars at the periphery of the circular cage. Since small sized prints might move outwardly of the cage these strands 23 and 24 are of advantage.

45 By referring to Fig. 1 of the drawing it will be seen that the deflecting-plate 12 has a curvature corresponding approximately to the curvature of that end of the receptacle remote therefrom. Also the distance between the periphery of the cage and deflecting-plate is approximately equal to the distance 50 between the periphery of the cage and that end of the receptacle remote from said deflecting-plate, these features being of advantage so that the cage will rotate by a limited force of flowing water.

55 It will be understood that any source of supply of clean water will be suitable if it is moved by pressure, as by a water-works system, or if moved by force of gravity. On account of the particular arrangement of parts 60 a very limited force of moving water will cause rotation of the cage and its contents.

65 It will be understood that the receptacle is not permanently connected to the service pipe. The upper end of the intake pipe 8 is disposed in communication with the service

70 pipe 9, but may be removed therefrom, and this is a desired feature to permit the receptacle to be inverted for removal of the water therein whenever required.

75 It will be noted that an unobstructed passageway for water is provided between the U-shaped holder-bars of the print-holder and the walls of the receptacle, and since the print-holder is circular in side elevation it will rotate readily by the movement of water under pressure delivered from the service-pipe, said receptacle being approximately of 80 semicircular form in side elevation so that the water may move freely for rotating said print-holder.

85 I claim as my invention,—

90 1. A print washer comprising a receptacle curved at its ends and bottom and having upright side walls provided with bearing-members, an intake water pipe projecting downwardly from the top into the receptacle at one of the ends thereof, an axle provided between its ends with a cylindrical body and journalled in said bearing-members, a plurality of U-shaped holder-bars disposed radially of and rigidly mounted in said cylindrical body, a plurality of radially disposed 95 U-shaped holder-bars pivotally mounted in said cylindrical body, flexible strands connecting the rigidly mounted holder-bars one with another, and flexible strands connecting the pivotally mounted holder-bars one with another.

100 2. A print washer consisting of a receptacle having an intake for water under pressure and provided with an overflow element, a print-holder of circular form in side elevation within and having an axle journalled in said receptacle below said intake and overflow element, holder-bars approximately of 105 U-shape disposed radially of and rigidly mounted in said axle, a plurality of holder-bars approximately of U-shaped pivotally mounted in said axle, strands connecting the rigidly mounted holder-bars one with another, and strands on the pivotally mounted holder-bars connecting them one with the other.

110 3. A print washer comprising a receptacle approximately semi-circular in side elevation, a pipe projecting downwardly into the receptacle for conducting water to be discharged near its bottom at one end thereof, a print-holder including an axle journalled in the receptacle, holder-bars approximately of 115 U-shape disposed radially and mounted on the axle, strands secured to and connecting one holder-bar with another holder-bar, said holder-bars being of such proportions that an unobstructed passageway for water will be formed between said bars and the walls of 120 said receptacle.

125 4. A print washer comprising an upright receptacle approximately of semicircular form open at its top, a print-holder of circu- 130

lar form disposed in the receptacle and including an axle having journalled bearings, holder-bars approximately of U-shape rigidly mounted upon and extending radially from the axle, a group of holder-bars approximately of U-shape pivotally mounted on the axle, a second group of holder-bars approximately of U-shape pivotally mounted on the axle, strands connecting the rigidly mounted bars one with the other, strands connecting the bars of the first named group of bars one with the other, springs removably connecting the bars of the first named group with the bars of the second group, and an intake-pipe for directing water under pressure against the holder-bars for rotating said print-holder.

5. A print washer comprising a receptacle open at its top, a print-holder in the receptacle including a journalled axle, holder-bars approximately of U-shape disposed radially and mounted in the axle, strands connecting said bars one with another, a deflecting-plate in the receptacle, and a pipe for conducting water under pressure into the receptacle and 25 against the deflecting-plate to cause rotatable movements of said print-holder.

In testimony whereof, I have affixed my signature.

CLYDE B. TRUSSELL.
